UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

APPARATUS FOR SOFTENING SHOES.

1,209,694.

Specification of Letters Patent.

Patented Dec. 26, 1916.

Application filed June 29, 1912. Serial No. 706,660.

To all whom it may concern:

Be it known that I, FREDERICK M. FURBER, a citizen of the United States, residing at Revere, in the county of Suffolk and State of Massachusetts, have invented certain Improvements in Apparatus for Softening Shoes, of which the following description, in connection with the accompanying drawings, is a specification, like reference characters on the drawings indicating like parts in the several figures.

This invention relates to apparatus for softening the toes or other portions of boots or shoes by the use of steam or vapor.

In connection with the lasting and pulling-over operations on shoes it has been found very advantageous to soften the toe box and upper in order to render the stock more pliable and thus to facilitate the molding of the upper over the toe of the last and the plaiting of the stock over the insole. While various forms of apparatus of this character have gone into general use, they are all, so far as I am aware, open to the objection that they require the exercise of considerable care to prevent the burning of the stock. This is particularly true if the apparatus is connected with a steam supply in which any considerable pressure is maintained.

It is, therefore, an important object of this invention to devise an apparatus of the character indicated in which the shoes can be treated without danger of injuring them and in which the temperature of the vapor can be readily controlled. I have found that this object can be conveniently accomplished by mixing air with steam and using this mixture to treat the shoe. The air appears to condense the steam sufficiently to produce a very moist vapor, which is desirable for this purpose, and yet which is cool enough to avoid any injury to the stock. The temperature of the vapor produced in this manner may be readily controlled by varying the relative proportions of the steam and air used in the mixture.

In the accompanying drawings I have shown, for purposes of explanation, an apparatus embodying the invention, which is designed particularly for use in softening the toe portion of the upper preparatory to the pulling-over operation.

Figure 1 is a perspective view of the apparatus showing a shoe in position to be treat-

ed: Fig. 2 is a vertical central sectional view of the apparatus shown in Fig. 1; and Fig. 3 is a horizontal sectional view through the steam and air inlets.

In the drawings, 2 indicates a long, thin casing designed to rest on a table or bench and having a pair of short legs 4 near its front side which support the floor of the casing in an inclined position. A hollow boss 6 projects from the rear wall of the casing and contains a steam chamber 8 and an air chamber 10, these chambers being separated by a partition 12. The steam chamber is connected, preferably at its lowest point, with a steam supply pipe 14. A valve 16 connected into this pipe at one side of the boss 6 controls the flow of steam therethrough, and a steam trap 18 connected into the pipe at the other side of the boss serves to carry away the condensed steam while preventing the flow of steam therethrough. Steam is admitted from the chamber 8 to the casing 2 through a nozzle 20 which consists of a tapered pin drilled transversely and longitudinally, and seated in a tapered hole 22 formed through the wall of the boss 6 and the partition 12. For purpose of withdrawing the nozzle from its seat when desired its rear end is reduced and threaded to receive a nut that bears against the back of the boss. The forward end of the nozzle projects through an aperture in the rear wall of the casing 2 and has several small diverging holes drilled therein, all lying substantially in a horizontal plane. These holes direct the steam into the casing in a fan-like jet and distribute it substantially uniformly throughout the casing. The steam escapes from the casing through a long, narrow slit 22 in the casing top.

A series of holes 24 are drilled through the wall of the boss 6 into the air chamber 10 to afford a free flow of air thereto. Since the steam is under pressure its escape in a jet into the casing through the nozzle 20 will cause a rarefaction in the surrounding medium, producing an innrush of air through the holes 24, which will become intimately mixed with the steam before it reaches the outlet 22. The quantity of air admitted in this manner may be controlled by closing as many of the holes 24 as may be found desirable, and for this purpose these holes are threaded to receive correspondingly threaded plugs. The water of condensation is car-

ried away by a drip pipe 26 set into a drain space formed at the lowest point of the chamber in the casing.

As previously stated, the apparatus shown is designed particularly for use in softening the toes of the shoe uppers preparatory to the pulley-over operation. At this point in the manufacture of the shoe the upper is loose on the last but usually is fastened thereto by a single tack driven through the back of the heel. It is desirable that the last shell be protected from the action of the steam or vapor and consequently, in order to support the work for the steaming operation the casing 2 is provided with a shelf-like rest 28 positioned below the inclined floor of the casing but extending substantially parallel therewith. The casing floor is extended beyond the outlet 22 and the lasts are placed in the space between the floor and the rest 28 with the uppers attached thereto extending over the top of the casing and across the outlet 22. The vapor issuing from the outlet strikes the lining and inner surface of the upper and spreads over the entire portion of the upper that it is desirable to soften. Preferably the casing 2, boss 6 and rest 28 are cast integrally.

In order to keep the part of the top of the casing on which the upper rests from becoming heated, a long, narrow slot 30 is cut through the casing top and the inrush of air through this slot caused by the flow of vapor through the casing maintains the top of the casing in a cool condition. This slot preferably is closed by a wire screen 32 held in position by a slotted plate 34 and screws 36.

In using the apparatus the steam is turned on by opening the valve 16. Its discharge into the casing causes it to draw air through the chamber 10, the relative arrangement of air and steam supplying devices causing the air to be directed against the jet of steam as it emerges from the nozzle and causing the steam to mix automatically with the air. This mixture flows rapidly through the casing out of the outlet 22 where it strikes the work which has been placed in the position shown in Figs. 1 and 2. The quantity of vapor can be controlled by adjusting the valve 16. I find that the temperature of the vapor is only slightly affected by variations in the quantity of the steam supplied, but if it is desired to increase the temperature of the vapor, this result may be accomplished by closing as many of the holes 24 as is found desirable. This adjustment decreases the quantity of air mixing with the steam, and since the delivery of steam remains constant, the temperature of the mixture will be raised.

The adjustment of the apparatus preferably is such that, while the temperature of the vapor is high enough to produce quickly

the desired softening effect on the upper stock, still it is low enough to avoid any danger of injuring the stock.

Having thus described by invention, what I claim as new and desire to secure by Letters Patent of the United States is:—

1. An apparatus for treating shoes, comprising shoe supporting means, a chamber in communication with a steam supply and with the atmosphere, the pressure of the steam in said chamber being less than that of the atmosphere, whereby a substantial current of air into said chamber is provided and said air and steam are intimately mixed, and means for directing the contents of said chamber on a shoe supported on said means.

2. An apparatus for treating shoes, comprising shoe supporting means, a steam chamber having an opening communicating with the atmosphere, the pressure in said chamber in the vicinity of said opening being less than that of the atmosphere, whereby a substantially uniform current of air flows into said chamber, and is intimately mixed with said steam, and means for directing the mixed air and steam on to a part of a shoe sustained by said means.

3. An apparatus for treating shoes, comprising a casing constructed to direct vapor on the part of the shoe to be treated, means for supplying steam to said casing, and means for utilizing the action of the steam while it is at a pressure greater than that of the atmosphere to cause it to become intimately mixed with air before it strikes the shoe.

4. An apparatus for treating shoes comprising a casing, a steam nozzle projecting into said casing, said casing being constructed and arranged to direct air against the steam as it emerges from said nozzle, and means for holding a shoe with a part thereof in position to be acted on by the vapor passing through the casing.

5. An apparatus for treating shoes, comprising a hollow casing having a long, narrow outlet in its upper surface, a steam inlet nozzle positioned in the back of said casing, said casing being constructed and arranged to admit air around the nozzle, and a rest located below the outlet of the casing in position to support a plurality of lasts with the shoe uppers supported on said lasts extending over said outlet.

6. An apparatus for treating shoes comprising a casing, means for supplying hot vapor to said casing, an outlet for the vapor, and a rest positioned to support a last with the shoe upper thereon extending over said outlet, said casing having an air intake opening located close to the position occupied by the upper.

7. An apparatus for treating shoes comprising a casing constructed to direct vapor on to the part of the shoe to be treated, a

nozzle having connections with a steam supply and positioned to direct steam into said casing, said casing having means for admitting air around and close to the discharge opening of said nozzle and a drain space below the nozzle, and a drain pipe opening into said space.

8. An apparatus for treating shoes comprising a casing, means for conducting steam and air into the back of the casing, said casing having an outlet for the steam and air, a work rest so located with respect to said outlet that the vapor passing therethrough will strike the work, said casing having an air intake opening in its top between the outlet and the steam inlet, and a drain pipe opening into the bottom of said casing.

9. An apparatus for treating shoes comprising a casing, a boss projecting from the rear wall of said casing, a steam delivery nozzle supported in said boss and constructed to distribute steam substantially uniformly throughout said casing, said boss having a series of holes to admit air close to the discharge end of said nozzle, said cas-

ing having a long, narrow outlet near its front side and an air intake opening in its top, and an inclined rest positioned along the front side of said casing to support the work, said rest, casing and boss being integral.

10. An apparatus for treating shoes, comprising the casing 2 having an inclined floor, the rest 28 integral with said casing and extending substantially parallel with said floor but spaced therefrom sufficiently to admit a series of lasts between the floor and said rest with the shoe uppers attached to said lasts lying on the top of said casing, and means for supplying vapor to said casing, said casing having a discharge outlet positioned to direct vapor against the uppers resting thereon.

In testimony whereof I have signed my name to this specification in the presence of two subscribing witnesses.
